UNITED STATES PATENT OFFICE.

CLYDE J. FITCH, OF BROOKLYN, NEW YORK, ASSIGNOR TO C. J. FITCH, INC., OF BROOKLYN, NEW YORK, A CORPORATION OF NEW YORK.

TELEPHONIC SPEAKER.

Application filed March 20, 1926. Serial No. 96,153.

This invention relates to the class of telephonic apparatus ordinarily known as "loud speakers".

Special objects of the invention are to improve and simplify apparatus of this general class, particularly as regards the actuating instrumentality or so-called telephone unit, the tympanum or member by which the electrical variations are converted into sound vibrations and the mounting or assembly of these parts in a practical desirable form.

The foregoing and other objects are attained by certain novel features of construction, combinations and relations of parts as hereinafter set forth.

In the drawings accompanying and forming part of this specification, different preferred embodiments of the invention are illustrated and it is to be understood that the structure may be further modified without departure from the broad spirit and scope of the invention as defined and claimed.

Figure 1 is a broken front elevation of a form of the invention as embodied in a combination cabinet-table structure.

Figure 2 is a vertical sectional view of the same.

Figure 3 is an enlarged broken sectional view illustrating particularly details in the mounting of the flexible cone and the attachment of the cone to the armature of the magnet.

Figure 4 is a vertical sectional view of a smaller form of the invention, involving slight modifications.

Figure 5 is a sectional view as on line 5—5 of Figure 4.

Figure 6 is an enlarged broken sectional detail of a modified form of armature structure.

Figure 7 is a broken diagrammatic representation illustrating the magnetic losses occurring when the magnetic gap is located outside the coil, and

Figure 8 is a similar view showing how this loss is prevented and the flux is obliged to cross the gap when the gap is located within the coil.

In the several illustrations, the tympanum or sound reproducer is in the form of a cone 1. In the first form of the invention shown, Figures 1 to 3, this cone is of fairly large size, say three feet or more in diameter and this fact makes it practical to combine the

cone with a table or cabinet structure. This table is shown as made up of four corner posts 2 connected at the ends by panels 3 and supporting a table top 4 and an inside bottom shelf 5. This construction leaves the front and back of the cabinet entirely open for sound propagation and provides a frame for the cone, which is mounted within the cabinet over the open front thereof and arranged with the apex of the same to the rear.

The cone is shown made with a rearwardly angled rim flange 6 and a simple convenient and practical method of positioning the cone is to glue or otherwise secure turned back flaps of this flange to the under side of the table top at 7, the top of the shelf at 8 and the inner sides of the posts at 9. These four points of connection at top, bottom and sides position and partially support the cone without hampering its sound producing vibrations.

The operating unit is shown as mounted on a bar 10 extending across the open back of the cabinet between the corner posts at a level substantially corresponding to the apex of the cone.

The construction described provides a table of general utility but particularly adaptable as a support for a radio receiving set, indicated at 11, with which the device is used and a compartment over the bottom shelf at the back of the cone for the batteries or other accessories 12 of the system. The open front and rear of the cabinet allow full propagation of sound waves at both sides of the cone and the closed ends of the cabinet appear to aid propagation of the sound, possibly in the capacity of sounding boards.

The interior of the cone may be painted or otherwise ornamented to give the cabinet a finished effect or, if desired, the cone may be covered over by a light ornamental curtain or screen 13 supported on curtain rods 14 extending across between the front corner posts.

The telephone unit which actuates the cone is of special construction, particularly in that the permanent magnet consists of a single straight bar magnet 15. This bar magnet in the illustration carries at one end a rigid polar projection 16, provided by an angled bracket of soft iron whose base 17 is secured flat against the end portion of the

bar by screws 18, 19. Secured to the opposite end of the bar by screw 20 there is shown a soft iron bracket piece 21 angled away from the bar and having attached to its upper offset end portion, a soft iron strip 22, having its upper end angled toward the rigid polar projection to form a companion polar extension 23. The strip 22 is sufficiently flexible to operate actually as an armature for the rigid polar projection 16.

The armature strip 22 is shown rigidly secured at its lower end to the lower polar projection 21 by a screw and nut at 24 and as rigidly secured to the upper end of the same projection by the nuts 25 on the extended portion of the screw bolt 19. This bolt is preferably of nonmagnetic material so as not to short-circuit any of the magnetic flux across the gap 26 between the polar projections 16, 23 but the screws and nuts at 18, 20, 24 may be and preferably are of magnetic material so as to preserve the full magnetic cross section at these points.

It will be observed that in addition to securing the armature strip rigidly to the end of the lower polar projection 21, the nuts 25 may be adjusted one way or the other on the bolt 19 so as to shift the bracket and the armature which it carries to increase or reduce the width of the gap at 26.

The opposed polar projections 16 and 23, the first of which is rigid and immovable and the second of which is flexibly supported and so may be regarded as an armature, are surrounded by an actuating or control coil 27. This coil is shown formed with an open center so as to provide a free operating space 28 for the movable armature and the coil is shown as positioned to enable this result by being supported on the rigid polar projection over an insulating bushing 29.

To secure the full effect of the electromagnet, the polar projection which forms the armature is preferably connected with the cone by a direct or substantially straight line connection. This connection is shown as a transmission link 30 engaged at one end directly with the end of the armature and at its opposite end with the apex of the cone.

In Figure 3 the transmission link is illustrated as a small stiff rod screwed at 31 into the elbow at the end of the armature and screw threaded at its opposite end to receive the nuts 32, 33, clamping the cone between them. A small metal washer 34 is shown engaged over the outside of the cone and over this a larger paper or like washer 35 glued or otherwise secured to the outer surface of the cone. Both the small metal washer and the larger paper washer are dished to fit the angle of the cone and similarly, the outer and inner securing nuts 32, 33 are indicated as concavely and convexly conical to fit and closely grip the parts clamped between them. The parts de-

scribed may be connected by riveting or soldering if desired, but the screw connections are preferred because of manufacturing and assembling advantages.

By actuating the cone or sound reproducing medium directly from the free end of the armature, the full operation of the unit is utilized and hence the maximum effect is obtained. This effect may be modified or reduced, however, very readily, if that is desired, by connecting the transmission link with the flexible portion of the elbow strip at a point more or less removed from the elbow at the end of the armature extension, the reduction in movement increasing as the point of connection approaches the fixed point represented by the clamp nuts 25.

Structurally, it will be seen that the invention is simple, practical and inexpensive, the operation is direct, positive, powerful and can be readily adjusted; the table-cabinet form of the device in addition to the superior acoustic advantages, is of an attractive, ornamental nature and particularly useful because of its supporting and housing characteristics for the receiving set and its accessories. To position the batteries or other accessories and prevent them from coming into contact with the back of the cone, suitable positioning stops may be provided on the supporting shelf, as indicated at 36 in Figure 2.

The location of the magnetic gap within the coil concentrates the flux and prevents or reduces leakage. This provides a particularly powerful unit, especially effective for cone and like reproducers operating in free air—that is, without a sound box or horn or the like. A large cone such as illustrated requires but comparatively small movement. The unit shown is particularly suited to this because the support for the armature, though flexible, is relatively stiff and the gap is quite small. The action of the unit, therefore, is quite powerful but the actual range of movement is small and suited to the direct actuation of a large cone without the interposition of any motion reducing connections. This form of armature also is suited to wholly supporting the cone.

To support the operating unit yieldingly so that there may be no reaction from the same which might have a tendency to set up vibrations in the console or cabinet, the same is shown mounted on the back bar by a cross strap 37 caught beneath the head of the screw bolt 19, the ends of said strap projecting far enough and being sufficiently flexible and resilient to absorb vibrations from the back of the permanent magnet. These spring supporting arms may be engaged by any suitable securing means such as the supporting screws indicated at 38.

The operating unit is of such sturdy construction that it may be relied upon to en-

tirely support the cone, particularly the smaller size cones. If desired, however, the edge of the cone may be allowed to rest against a ring of felt or the like, as indicated at 39, Figure 4. This felt ring is shown as carried by a circular frame 40 which may form part of the front of the cabinet.

The small metal washer 34 which is engaged over the outside of the cone forms a substantially rigid element for the anchorage of the transmission link and the larger paper washer 35 which is glued over the metal washer and over the back of the cone serves both as a means for securing the metal washer to the cone and as a means for bracing and stiffening the central portion of the cone. The metal cone, furthermore, acts in the nature of a cup or seat for supporting the cone.

If desired, the armature may be formed as an element separate from the resilient supporting strip, as indicated at 23' in Figure 6 and this construction permits of the transmission link being utilized as a fastening for securing the parts together, it being shown as having its threaded inner end extending freely through an opening in the resilient supporting strip 22 and into a screw seat 41 in the end of the armature member, a cross seat 42 formed in the supporting strip preventing the armature block from twisting under the action of screwing the transmission rod thereinto.

35. What is claimed is:

1. In combination, a permanent bar magnet, a polar projection extending from one end of said magnet, a rigid magnetic bracket secured to the opposite end of said bar magnet, a yieldable magnetic strip secured to said rigid bracket and having a polar projection opposed to the first polar projection, a magnet winding associated with said polar projections and a sound reproducing member connected with the flexibly supported polar projection.

2. In combination, a permanent bar magnet, a polar projection extending from one end of said magnet, a rigid magnetic bracket secured to the opposite end of said bar magnet, a yieldable magnetic strip secured to said rigid bracket and having a polar projection opposed to the first polar projection, a magnet winding associated with said polar projections and a sound reproducing member connected with the flexibly supported polar projection, said magnet winding being hollow and supported by being engaged at one end over the first polar projection, the opposite open end of said magnet freely receiving the flexibly supported polar projection.

3. In apparatus of the character disclosed, a permanent magnet having a fixed polar projection, a flexible magnetic strip magnet-

ically connected with the opposite pole of said magnet and having an angularly bent end portion projecting toward the fixed polar projection to form an armature therefor, a transmission link connected with said armature substantially at the bend mentioned, a sound reproducing member engaged by said link and a magnet winding acting on said armature.

4. In apparatus of the character disclosed, 75 an electromagnetic unit comprising a bar magnet, a polar extension for said magnet, a spacing bolt for securing said polar extension and a cross strap for mounting the unit secured to the bar magnet by said spacing bolt.

5. In apparatus of the character disclosed, a permanent bar magnet having a polar element at one end, a polar extension of less cross sectional area than the bar magnet 85 extending from the opposite end of said magnet toward said first mentioned end and a resilient member of less cross sectional area than said extension forming a continuation of said extension and carrying a polar element opposed to said first polar element.

6. A telephonic speaker unit comprising a permanently magnetized substantially straight magnet bar, a bracket of magnetic material having angularly related sides, one 95 side being secured to one end of the bar as a base and the other side projecting angularly from the end of the bar as a polar extension, a second magnetic bracket, said second bracket having one end secured to the opposite end of the magnet bar and extending therefrom in offset relation toward the first mentioned end of the bar, a polar extension at the other end of said second bracket projecting angularly toward the polar extension of the first bracket, a vibration transmission connection engaged with said second polar extension and a magnet winding associated with the polar extensions.

7. A telephonic speaker unit comprising a permanently magnetized substantially straight magnet bar, a bracket of magnetic material having angularly related sides, one side being secured to one end of the bar as a base and the other side projecting angularly from the end of the bar as a polar extension, a second magnetic bracket, said second bracket having one end secured to the opposite end of the magnet bar and extending therefrom in offset relation toward the first mentioned end of the bar, a polar extension at the other end of said second bracket projecting angularly toward the polar extension of the first bracket, a vibration transmission connection engaged with said second polar extension, a magnet winding surrounding said opposed polar projections and screw means variably spacing the offset portion of the second bracket from the bar to regulate the magnetic gap between 110 115 120 125 130

the polar extensions within the magnet winding.

8. A telephonic speaker unit comprising a permanently magnetized substantially straight magnet bar, a bracket of magnetic material having angularly related sides, one side being secured to one end of the bar as a base and the other side projecting angularly from the end of the bar as a polar extension, a second magnetic bracket, said second bracket having one end secured to the opposite end of the magnet bar and extending therefrom in offset relation toward the first mentioned end of the bar, a polar extension at the other end of said second bracket projecting angularly toward the polar extension of the first bracket, a vibration transmission connection engaged with said second polar extension and a magnet winding associated with the polar extensions and screw means for variably spacing the offset portion of the second bracket in relation to the bar to regulate the gap between the polar extensions.

25 9. A telephonic speaker unit comprising a permanently magnetized substantially straight magnet bar, a bracket of magnetic material having angularly related sides, one side being secured to one end of the bar as a base and the other side projecting angularly from the end of the bar as a polar extension, a second magnetic bracket, said second bracket having one end secured to the opposite end of the magnet bar and extending therefrom in offset relation toward the first mentioned end of the bar, a polar extension at the other end of said second bracket projecting angularly toward the polar extension of the first bracket, a vibration transmission connection engaged with said second polar extension and a magnet winding associated with the polar extensions, the base of the first bracket being secured to the bar by a screw stud and said screw stud being engaged with the offset portion of the second bracket to position the same relative to the bar.

50 10. A telephonic speaker unit comprising a permanently magnetized substantially straight magnet bar, a bracket of magnetic material having angularly related sides, one side being secured to one end of the bar as a base and the other side projecting angularly from the end of the bar as a polar extension, a second magnetic bracket, said second bracket having one end secured to the opposite end of the magnet bar and extending therefrom in offset relation toward the first mentioned end of the bar, a polar extension at the other end of said second bracket projecting angularly toward the polar extension of the first bracket, a vibration transmission connection engaged with said second polar extension and a magnet winding associated with the polar exten-

sions, the base of the first bracket being secured to the bar by a screw stud and said screw stud being engaged with the offset portion of the second bracket to position the same relative to the bar and a mounting strap for the unit held to the bar by said same screw stud.

5 11. A telephonic speaker unit comprising a permanently magnetized substantially straight magnet bar, a bracket of magnetic material having angularly related sides, one side being secured to one end of the bar as a base and the other side projecting angularly from the end of the bar as a polar extension, a second magnetic bracket, said second bracket having one end secured to the opposite end of the magnet bar and extending therefrom in offset relation toward the first mentioned end of the bar, a polar extension at the other end of said second bracket projecting angularly toward the polar extension of the first bracket, a vibration transmission connection engaged with said second polar extension and a magnet winding associated with the polar extensions, the base of the first bracket being secured to the bar by a screw stud and said screw stud being engaged with the offset portion of the second bracket to position the same relative to the bar and a mounting strap for the unit held to the bar by said same screw stud, the second polar extension being a separate strip held to the offset portion of the second bracket by said same screw stud.

25 12. A telephonic speaker unit comprising a permanently magnetized substantially straight magnet bar, a bracket of magnetic material having angularly related sides, one side being secured to one end of the bar as a base and the other side projecting angularly from the end of the bar as a polar extension, a second magnetic bracket, said second bracket having one end secured to the opposite end of the magnet bar and extending therefrom in offset relation toward the first mentioned end of the bar, a polar extension at the other end of said second bracket projecting angularly toward the polar extension of the first bracket, a vibration transmission connection engaged with said second polar extension and a magnet winding associated with the polar extensions, said second polar extension being a separate flexible strip secured to the offset portion of the second bracket.

50 13. A telephonic speaker unit comprising a permanently magnetized substantially straight magnet bar, a bracket of magnetic material having angularly related sides, one side being secured to one end of the bar as a base and the other side projecting angularly from the end of the bar as a polar extension, a second magnetic bracket, said second bracket having one end secured to the opposite end of the magnet bar and extend-

- ing therefrom in offset relation toward the first mentioned end of the bar, a polar extension at the other end of said second bracket projecting angularly toward the 5 polar extension of the first bracket, a vibration transmission connection engaged with said second polar extension and a magnet winding associated with the polar extensions, said second polar extension being a 10 separate flexible strip secured to the offset portion of the second bracket and said offset portion being rigidly secured to the bar in spaced relation and the flexible strip projecting freely beyond such rigidly held portion.
14. A telephonic speaker unit comprising a permanently magnetized substantially straight magnet bar, a bracket of magnetic material having angularly related sides, one 20 side being secured to one end of the bar as a base and the other side projecting angularly from the end of the bar as a polar extension, a second magnetic bracket, said second bracket having one end secured to the 25 opposite end of the magnet bar and extending therefrom in offset relation toward the first mentioned end of the bar, a polar extension at the other end of said second bracket projecting angularly toward the 30 polar extension of the first bracket, a vibration transmission connection engaged with said second polar extension and a magnet winding associated with the polar extensions, the base of the first bracket being secured to the bar by a screw stud and said screw stud being engaged with the offset portion of the second bracket to position the 35 same relative to the bar, said screw stud being of non-magnetic material and having 40 fastening nuts thereon of magnetic material.
15. A telephonic speaker unit comprising separately formed legs rigidly secured together at one end and spaced at their opposite ends to constitute a magnet yoke, one 45 of said legs being a permanent magnet and the other being only of magnetizable material, opposed polar projections at the ends of said legs, a magnet winding associated with said polar projections and a strut connecting the 50 legs of the yoke, said strut having means of adjustment enabling variations in the relation of the non-permanent to the permanent magnet leg.
16. A telephonic speaker unit comprising 55 separately formed legs rigidly secured to-
gether at one end and spaced at their opposite ends to constitute a magnet yoke, one of said legs being a permanent magnet and the other being only of magnetizable material, opposed polar projections at the ends of said legs, a magnet winding associated with said polar projections and a strut connecting the legs of the yoke, said strut having means of adjustment enabling variations in the relation of the non-permanent to the permanent magnet leg and the polar projection of one of the legs being flexible beyond said strut. 60
17. A telephonic speaker unit comprising a permanently magnetized magnet bar, a pole piece at one end of said bar, a rigid 70 magnetic bracket secured to the opposite end of said bar, a strut securing the free end of said bracket rigidly spaced from the body of the bar, a yieldable magnetic strip secured to said rigidly held bracket and projecting 75 beyond said strut, a polar projection carried by said projecting portion of the yieldable strip in opposition to the pole piece of the bar and a magnet winding associated with said pole piece. 80
18. A telephonic speaker unit comprising a permanently magnetized magnet bar, a pole piece at one end of said bar, a rigid magnetic bracket secured to the opposite end of said bar, a strut securing the free end 85 of said bracket rigidly spaced from the body of the bar, a yieldable magnetic strip secured to said rigidly held bracket and projecting beyond said strut, a polar projection carried by said projecting portion of the yieldable strip in opposition to the pole piece of the bar and a magnet winding associated with said pole piece, said strut also securing said strip to the bracket and having means enabling adjustment of the two 90 relative to the magnet bar. 95
19. A telephonic speaker unit comprising a permanently magnetized substantially straight magnet bar, brackets of magnetic material having base portions secured in 100 flat engagement with the same side of said bar at opposite ends of the same, said brackets being angled away from said side of the bar and provided with opposed pole pieces separated by a magnetic gap and movable 105 one with respect to the other and a magnet winding surrounding said pole pieces.

In witness whereof, I have hereunto set my hand this 9th day of March, 1926.

CLYDE J. FITCH.
